UNITED STATES PATENT OFFICE.

CLARENCE D. PLATT, OF BRIDGEPORT, CONNECTICUT.

DESIGN FOR AN ELECTRIC-SWITCH MEMBER.

14,690.

Specification for Reissued Design. Reissued July 15, 1919.

Original No. 51,869, dated March 12, 1918, Serial No. 138,510, filed December 22, 1916, for $8\frac{1}{2}$ years. Application for reissue filed April 12, 1919. Serial No. 289,770. Term of patent 14 years.

To all whom it may concern:

Be it known that I, CLARENCE D. PLATT, a citizen of the United States, residing at Bridgeport, Fairfield county, Connecticut, have invented a new, original, and ornamental Design for an Electric-Switch Member, of which the following is a specification, reference being had to the accompanying drawing, illustrative of the same and forming part thereof, in which—

Copies of this patent may be obtained for five cents each, by addressing the "Commissioner of Patents, Washington, D. C."

Figure 1 is a perspective view of the switch member embodying my new, original and ornamental design.

Fig. 2 is a side view of the same.

I claim—

The design for an electric switch member substantially as shown.
